UNITED STATES PATENT OFFICE

CHARLES VALLONE, OF BUFFALO, NEW YORK, ASSIGNOR TO BARCALO MANUFACTURING COMPANY, OF BUFFALO, NEW YORK

HOLDER FOR SOCKET WRENCH SETS

Application filed September 18, 1928. Serial No. 306,688.

This invention relates to improvements in holders for socket wrench sets, and which sets usually comprise a number of sockets of graduated sizes, and a bent handle, to either end 5 of which a socket can be detachably secured for use.

The objects of the invention are to construct an improved, simplified and inexpensive socket wrench set holder; also to provide a novel holder for this purpose, in which the sockets are supported in spaced and classified relation, prevented from any substantial lateral or endwise movement, and which may be formed in a simple manner of pressed 10 sheet metal; also to provide a holder of this kind to which the handle of the socket set can be quickly and detachably secured in a position for retaining the sockets in place on the holder; also to improve the construction 15 of holders for socket wrench sets in the other respects hereinafter set forth.

In the drawing: Fig. 1 is a side elevation of a socket wrench set secured in a holder constructed in accordance with and embodying 20 the invention.

Fig. 2 is a plan view thereof with the handle for the sockets partly broken away;

Fig. 3 is a longitudinal, vertical section 25 thereof, with certain of the sockets omitted; Fig. 4 is an end elevation thereof;

Figs. 5 and 6 are transverse, vertical sections thereof, on lines 5—5 and 6—6, respectively, Fig. 1;

Fig. 7 is a fragmentary, longitudinal section 30 of one end of the holder, on an enlarged scale, on line 7—7, Fig. 4;

Fig. 8 is a plan view of the holder with the tools removed;

The socket wrench set for which the holder 40 of the present invention is intended comprises a plurality of sockets 10 of graduated sizes, and an L-shaped handle 11 formed of a bar of polygonal cross section and comprising a relatively long, straight arm or portion 12 and a short arm or bent-over end portion 13 extending substantially at right angles thereto.

The sockets 10 are of somewhat cylindrical 45 form and of substantially equal length, and each is formed with a large end 14 and

a reduced end 15 separated by a transverse, annular shoulder 16. The shoulders of all sockets are the same distance from the outer end of the nut engaging aperture or cavity. The large ends 14 of the sockets are formed 55 with lengthwise apertures, each of a different size for engaging work such as nuts, bolt heads and the like, while the reduced ends 15 of all the sockets are also preferably of graduated sizes and each provided with a 60 longitudinal hole corresponding approximately in size and shape to the cross section of the handle 11, and is adapted to receive either the bent-over end or arm 13 or the 65 opposite end of the arm 17 thereof.

The handle 15 is provided near each end with suitable stop means 18 for limiting the extent to which the handle enters the sockets, and between said stop means and the adjacent extremity of the handle a suitable friction catch or holding member, such as a spring pressed ball 19 is provided, which when a socket is applied to an end of the handle, frictionally engages the wall of the handle-receiving aperture therein, and detachably retains the socket in place thereon.

The improved holder 20 for socket wrench sets of the type described is preferably a single sheet metal, channel shaped stamping, having a narrow horizontal web 21 and opposite, depending side flanges 22 extending lengthwise of the holder.

The web 21 is provided with a plurality of holes or apertures 23 arranged in spaced relation and preferably graduated in size, 85 which sizes correspond to the graduated sizes of the reduced ends of the sockets, and which form seats for the reception of the sockets 10.

Each aperture or seat 23 is of such size that by inserting the reduced end 15 of the socket intended for that seat downwardly into the latter, the shoulder 16 will engage and rest on the edges of the seat, and the socket will fill the aperture and be held against rattling or lateral displacement. The 90 sockets are thus supported in spaced relation with their large ends 14 projecting a uniform distance above the holder.

The handle 11 may be detachably connected to and arranged on the holder 20, as shown, 100

with its long, straight portion or arm 12 extending lengthwise over and disposed closely adjacent the upper, enlarged ends 14 of the sockets, and with the short arm or bent-over end of said handle depending at one end of said row of sockets, so that the sockets 10 are held in place on their seats 23 and substantially prevented from endwise movement out of the latter by said handle portion 12.

For thus supporting the handle, the holder 20 is provided with an upstanding transverse arm or projection 25, formed, for example, of an extended portion of the web 21, and which has an aperture 25a disposed so as to somewhat loosely receive the end 17 of the handle when in the position shown.

At its opposite end, the holder is formed so that the short arm or bent-over end 13 of the handle can be detachably but firmly connected thereto, and for this purpose the web 21 of the holder is provided with an additional seat or opening 26 adjacent the end socket seat 23. This seat 26 preferably corresponds to the cross sectional shape, and is approximately of the same or only slightly greater dimensions than the handle 11. Therefore, by first inserting the end 17 of the handle 11 into the aperture 25a and then bringing the downwardly extended, bent-over end 13 of said handle into registration with and inserting the same into the seat 26, this end of the handle can be releasably connected to the holder by merely exerting sufficient downward pressure on said handle to force the spring catch 19 past the edge of or through the seat 26.

The stops 18, in this operation, will engage the upper face of the web 21 and limit the extent to which the part 13 enters the seat 26.

The edge of the seat 26, if desired, can be flanged or beaded downwardly as at 27, see Fig. 6, the depth of said flange preferably being substantially equal to the distance between the catch 19 and said stops 18, so that said catch will engage the one side of said holder 20 and the stops 18 the other side. The handle will thus be releasably confined to said holder and firmly held in socket-retaining position.

The handle can be readily detached, to permit the removal of the sockets, by a slight upward pressure on the lower extremity of the bent-over end or arm 13.

The general shape of the holder 20 and the arrangement of the socket wrench set thereon is such that the holder can rest on a supporting surface with the edges of the flanges 22 engaging the latter. The depth of these flanges 22 is preferably made somewhat greater than the length of the reduced portions 15 of the sockets 10, see Fig. 3, so that said sockets are supported on their seats out of contact with said supporting surface.

As shown in Figs. 2, 4 and 7, the projection or arm 25 is reinforced by means of one or more corrugations 30 extending lengthwise or vertically of said arm. These corrugations 30 are preferably extended to the adjacent portion of the web 21, thus passing over and strengthening the transverse connecting angle 31 between said web and said arm, and acting to prevent the arm from being bent out of position under ordinary conditions of use.

The socket wrench set holder described is of relatively simple and inexpensive construction, being made of a single sheet metal stamping. The holder is strong and durable and the wrench handle can be readily and easily applied to the holder for retaining the sockets thereon, or disconnected therefrom for giving access to the sockets. The spaced seats in the holder retain the sockets in an orderly and classified arrangement and prevent them from shifting laterally on the holder, or being assembled out of order on the holder. Inasmuch as the distance from the shoulders 16 to the outer ends of the nut-receiving cavities is uniform for all the sockets, the projecting ends of the sockets when assembled on the holder will all lie in substantially the same plane, and the handle will lie closely along all of the sockets.

I claim as my invention:

1. A holder for a wrench outfit of the type comprising a plurality of individual sockets having large and small ends separated by a transverse shoulder, and a bar handle therefor, said holder comprising a horizontal channel shaped member having a web and depending side flanges and having a row of spaced seats in the web thereof for individually supporting said sockets with their shoulders resting upon said web and their small ends depending between the flanges of said holder, and interengaging means at opposite ends of said holder and said handle for releasably retaining the latter in a lengthwise position over the large ends of said sockets for holding them in their seats.

2. A holder for a wrench outfit of the type comprising a plurality of individual sockets having large and small ends separated by a transverse shoulder, and a bar handle therefor, said holder comprising a horizontal channel shaped member having a web and depending side flanges and having a row of spaced seats in the web thereof for individually supporting said sockets with their shoulders resting upon said web and their small ends depending between the flanges of said holder, and interengaging means at opposite ends of said holder and said handle for releasably retaining the latter in a lengthwise position over the large ends of said sockets for holding them in their seats, said interengaging means including an upstanding integral extension of one end of said web having an aper-

ture in which one end of said handle releasably engages.

3. A holder for a wrench outfit of the type comprising a plurality of individual sockets having large and small ends separated by a transverse shoulder, and a bar handle therefore, said holder comprising a horizontal channel shaped member having a web and depending side flanges and having a row of spaced seats in the web thereof for individually supporting said sockets with their shoulders resting upon said web and their small ends depending between the flanges of said holder, and interengaging means at opposite ends of said holder and said handle for releasably retaining the latter in a lengthwise position over the large ends of said sockets for holding them in their seats, said interengaging means including an upstanding integral extension of one end of said web having an aperture in which one end of said handle releasably engages, and said web extension and the adjoining portion of the web being reinforced by a bead extending lengthwise thereof and across the angle therebetween.
